**MACHINES FOR LASTING THE TOE
 ENDS OF SHOES**
 Charles Georges Jourdan, Rue Pailhery,
 Romans, France
 Filed June 21, 1966, Ser. No. 559,300
 Claims priority, application France, May 5, 1966,
 60,371
3 Claims. (Cl. 12—8.8)

The present invention has as its object a machine for lasting the toe ends of shoes, and relates more specifically to a distribution device for machines intended for assembly of the end of the upper and insole on a last, at the front extremity of the shoe.

Machines of many types are available, by means of which this operation may be performed mechanically. A very complete description of a machine of this nature may be found, for example, in the patent application filed in the United States of America on Jan. 22, 1959 under the number Ser. No. 788,396 in the name of A. W. Rockwell et al., now Patent No. 3,022,527.

Irrespective of the particular method of operation of the said machines, their working principle may be summarised as follows:

The upper being secured provisionally in the area of the heel, for example by means of tacks or sprig nails, its front portion is stretched by means of a certain number of pincers or the like, which are situated around the toe end of the last, and whereof the tension is adjustable in respect of force, direction and duration.

The upper is positioned correctly on the last, in this manner.

An element of stirrup-shape or analogous shape, co-operating with the last, ensures that the upper is held on the last in the last position. An element referred to as a distributor, arranged in horseshoe shape on the front of the last and below the same, then intervenes to distribute the fullness of the upper.

Another element of the machine, referred to as "wipers," then acts on the marginal portion of the upper referred to as "lasting margin," in order to fold the same down and secure it under the insole, by gluing for example. At the beginning of this operation, the upper is prevented from slipping, after previously having been held under tension by the said pincers, by keeping the same wedged between the said wipers and the said distributor which are brought into opposition.

These machines suffer from many shortcomings as a rule, especially if the upper comprises one or more linings. The assembly must then be glued before lasting, which is an additional operation increasing the lasting period and thus production cost of the shoes.

On the other hand, these uppers which may comprise two or three layers, are not easily fitted on the insoles in correct manner, owing to their thickness and possible slip of the different elements relative to each other.

The device according to the invention is intended to eliminate these shortcomings, employing a form of construction which is simple and strong, operates reliably and may easily be adapted to the known machines for lasting the toe ends of shoes.

It is a further object of the invention to simplify the operation of fitting the upper on the insole, specifically in the case of shoes with lined uppers.

Another object of the present invention is to produce shoes of better quality, without increase in cost price, while preventing any excessive thickness of the skin folded under the insole.

In a machine for lasting shoes, of the kind comprising wipers arranged to fold the toe end of an upper stretched

2

on a last, that is to say for folding the same under an insole, the present invention has as its object an improved distributor device co-operating with the said wipers in order to distribute the fullness of the upper, comprising an extremity coming into contact with the upper, which in characteristic manner comprises a cutting edge extending in such direction as to sever a definite fraction of the thickness of the part of the upper folded under the insole, and adjusting means for limiting the penetration of the cutting edge of the distributor into the upper, in order to set the cut thickness of the same.

During the final working operation of the machine described hereinabove, the said distributor and the said wipers are brought into opposition in order to grip the lasting margin intended to be secured under the insole, whilst keeping the same stretched around the last. The said wipers then perform an advancing and closing motion, thereby folding the lasting margin of the upper under the insole. According to the invention, during this motion, a fraction of the thickness of the said lasting margin is cut away by the cutting edge of the said distributor, which performs a planing action on the inner face of the said lasting margin of the upper.

The thickness to be cut from the said lasting margin may be adjusted to any value desired by limiting the depth of penetration of the cutting edge of the said distributor into the thickness of the upper, when the said wipers and the said distributor are made to co-operate to grip the upper, by means of an appropriate device such as a displaceable stop or the like.

For shoes whereof the uppers comprise two or three layer in particular, the penetration of the distributor may be adjusted in such manner as to cut the lining or linings only, and as to fold only the thickness of the upper itself under the insole.

According to a first form of embodiment of the invention, the said distributor is made in one piece, whereof the edge coming into contact with the upper has its outer periphery sharpened.

According to another form of embodiment of the invention, the cutting edge of the said distributor advantageously consists of a blade affixed to the same, made of hard steel for example, which may be secured in directionally adjustable manner or not, on the upper extremity of the said distributor by means of clamping screws or of any other appropriate fastening devices.

The machines equipped with the cutting distributor of the present invention provide a considerable saving of time in the fitting of the upper on the insole, eliminating the preliminary gluing of the lining or linings on the upper.

The cutting edge of the said distributor preferably extends on either side of the toe end of the shoe, throughout the area of counterpressure.

It is apt to note that the device according to the invention, whether consisting of a distributor of integral construction or comprising a blade secured on a conventional distributor, may easily be adapted to fit most of the existing machines without modification of their structure or operation.

The invention will now be described with reference to the accompanying drawings which show an embodiment of the invention, but in no restrictive sense.

FIGURE 1 is a diagrammatic plan view of the top part of a machine for lasting the toe ends of shoes, of the type described in the United States patent application referred to.

FIGURES 2a, 2b and 2c are diagrammatic sections along the line I—I of FIGURE 1, showing three successive stages in the operation of lasting the toe end of a shoe according to a known method.

FIGURE 3 is a plan view of the cutting distributor device according to the present invention.

FIGURE 4 is a section taken along the line IV—IV of FIGURE 3.

FIGURES 5a, 5b and 5c illustrate views analogous to those of FIGURES 2a, 2b and 2c, showing three successive operations in the lasting of the toe end of a shoe in a machine equipped with the cutting distributor device according to the present invention.

The machine illustrated in FIGURE 1 comprises a shoe bearer or the like 10, which is displaceable in the vertical direction and carries a last L covered with an upper comprising a marginal part M. An insole I is placed on the said bearer 10 under the last L.

Articulated wipers 1 are situated laterally on either side of the last L and may be folded inwards to apply the marginal part M of the upper U against the insole I situated under the last L.

A distributor 2 of a shape complementary to that of the toe end of the shoe which is to be lasted, co-operates with the wipers 1 to distribute the fullness of the upper U.

At the beginning of the lasting operation, the upper U is stretched on the last L by means of a toe end claw or the like 3, and of directionally adjustable lateral claws 3'.

FIGURE 2a shows the upper stretched by the toe end claw 3 on the last L placed on the said bearer 10 which occupies its initial position.

In FIGURE 2b, the bearer 10 has been displaced upwards and the wipers have begun to fold the marginal part M of the upper U under the insole I.

It will be noted that the upper U is no longer tensioned by the claw 3 which has been opened, but is wedged between the wipers 1 and the distributor 2 which thus hold the same in position on the last L.

In FIGURE 2c, the operation of lasting the toe end of the shoe is finished. The marginal part M of the upper U has been folded wholly under the insole I, to which it is to be secured, by gluing for example.

It is apt to note that the marginal part M folded under the insole I has the same thickness as the rest of the upper U.

FIGURES 3 and 4 illustrate the distributor device according to the present invention.

This distributor device comprises a normally horizontal unit 6 of a shape complementary to that of the toe end of the last L, and a normally vertical bottom extension 7 endowed with pegs or studs 8 by means of which the said distributor may be secured on a corresponding supporting member of the machine.

The upper portion 6 comprises a top edge 4 having a cutting edge situated in a plane substantially parallel to that of the wipers.

The said distributor is of integral construction in the form of embodiment illustrated in FIGURES 3 and 4.

In another form of embodiment of the distributor according to the present invention, the cutting part may advantageously consist of a component, being a steel blade for example, which may be secured in directionally adjustable manner on the body of the distributor by any appropriate devices, such as rivets, or bolts for example.

During the lasting operation, the cutting edge 4 of the distributor is brought into contact with the inner surface of the lasting margin M of the upper U, in manner to be described hereunder, in order to cut down its thickness by a fraction.

FIGURES 5a to 5c show a diagrammatic illustration in vertical section of a machine for lasting the toe ends of shoes, of a type analogous to that illustrated in FIGURE 1 but whereof the distributor 2 is replaced by a distributor 2' comprising a cutting edge 4, as described in respect of FIGURES 3 and 4.

In FIGURE 5a, the last L covered with an upper U with a lasting margin M tensioned by the end claw 3, occupies a low initial position on the bearer 10.

In FIGURE 5b, the bearer 10 has been displaced upwards and the wipers 1 have been started on their inward displacement to fold the margin M under the insole I. During this displacement, the claw 3 is opened and the margin M is wedged between the wipers 1 and the distributor 2'. The cutting edge 4 of the distributor 2' has started to penetrate into the thickness of the upper U, cutting a fraction 5.

To limit the thickness cut in the upper by the cutting edge 4, an abutment device may be employed to adjust the gap present between the wipers 1 and the edge 4 when these two elements co-operate to distribute the fullness of the skin to be folded under.

In FIGURE 5c, the operation of lasting the toe end of the shoe has been completed. A fragment, dropping away as a cut-off, has been severed by the cutting edge 4 of the distributor from the thickness of the margin M of the upper U.

The thickness of the margin M folded under the insole I is smaller than that of the upper U. If this upper comprises two or three layers in particular, the penetration of the cutting edge 4 may be adjusted in such manner as to cut only the said linings.

This ensures elimination of any superfluous thickness in the area of the toe end.

A machine comprising the said cutting distributor according to the present invention may thus be employed for lasting a shoe in simpler, faster and cheaper manner, whilst improving its quality.

30 I claim:

1. A machine for lasting the toe ends of shoes on a last by assembly of an upper and insole, comprising a displaceable last bearer or the like, pincers for stretching the said upper, wipers intended for inward movement folding against the said insole of the lasting margin of the said upper stretched on the said last, and entraining devices for displacing the said last bearer, for opening and closing the said pincers and for actuating the said wipers, in which an improved distributor device is of shape complementary to that of the last and has an edge coming into contact with the inner surface of the said lasting margin of the said upper and co-operating with the said wipers after the opening of the said pincers and at the start of the inward displacement of the said wipers intended to distribute the fullness of the said upper and hold the same stretched on the said last, the said distributor device comprising a cutting edge situated in a plane substantially parallel to that of the said wipers and directed outwards, for cutting a fraction of the thickness of the said lasting margin of the upper held between the said wipers and the edge of the said distributor, and devices for adjusting the relative positions of the said wipers and of the said distributor being incorporated to control the penetration of the cutting edge of the said distributor into the thickness of the said lasting margin of the upper.

2. A machine as claimed in claim 1, in which the said cutting edge is an integral part of the said distributor.

3. A machine as claimed in claim 1, in which the said cutting edge is wrought on a separate component which may be fastened in removable and directionally adjustable manner on the said distributor.
